BAG FILLING MACHINE

Harry S. Gay, Mount Gay, W. Va.

Application May 18, 1937, Serial No. 143,356

2 Claims. (Cl. 226—58)

This invention relates to improvements in bag filling machines, and its objects are as follow:

First, to provide a machine especially adapted to filling tamp bags with screened clay, these bags being used to force home charges of blasting powder in holes drilled in coal veins and the like.

Second, to provide a bag filling machine for the foregoing purpose which has as one of its main features that construction whereby the auger, auger tube and nozzle are easily separated from the rest of the machine and replaced.

Third, to improve the end of the nozzle so that a bag can be slipped on more easily and quickly than otherwise.

Fourth, to provide a novel belt tensioning arrangement wherein the weight of the motor is employed to stretch the belt, the belt also acting as a friction release in the event of a piece of iron or other solid matter getting into the auger.

Fifth, to provide a machine having the foregoing characteristics, which is readily adaptable to filling bags with materials other than screened clay for purposes other than tamping blasting powder charges.

Other objects and advantages will appear in the following specification, reference being had to the accompanying drawing, in which:

30 Figure 1 is a perspective view of the improved machine, both illustrating its use and diagrammatically showing the current control.

Figure 2 is a fractional longitudinal section of the machine.

35 Figure 3 is a detail sectional view which is a continuation of Fig. 2 at the line *a—b*.

Figure 4 is a detail perspective view of the forward end of the nozzle.

40 Figure 5 is a detail view of the hopper blank. As already indicated in one of the statements of the objects of the invention, the primary purpose of the instant machine is to enable the quick and easy filling of bags with clay, which is usually screened, so as to form plugs with which 45 to tamp charges of blasting powder in drilled holes. These bags are usually about 15 inches long, and when filled, as stated, are either dropped or forced into the hole so as to drive the charge of blasting powder home.

50 In carrying out the invention provision is made of a base generally designated 1. This comprises four legs 2 which are made of sections of pipe which are screwed into floor flanges 3 at one end, the other ends being appropriately secured to a 55 table 4 upon which all of the remaining mecha-

nism is mounted. The foregoing construction of the base 1 is not necessarily adhered to in practice because it is obvious that its purpose of supporting the mechanism can be served just as well by a structure which varies from that shown. 5

A clay hopper 5 is supported upon the table 4 by a plurality of upright braces 6 which are secured at their ends to the hopper and to the table. The hopper is made from a blank 5a, substantially of the shape in Fig. 5, and when medially bent tapers downwardly to a curved or tubular terminal 7. A flange 5b on the blank is formed into the spout or extension 8 (Fig. 2), which is long enough to extend beyond the front limit of the hopper and bridge the gap between the hopper and nozzle and prevent the loss of the material 11. The hopper is completed by end pieces 12 which are fitted in and secured in any customary manner. 15

The spout 8 is introduced into the top of a 20 support 13 onto which it is clamped by a cap 14. A similar support 13a extends up to where it is welded at 13b to the adjacent hopper end 12. A ball bearing 16 fits in a retainer 16a on the support 13a, a bearing retainer plate 16b holding the 25 ball bearing in place because of the two screws 16c which are driven through. The ball bearing 16 supports the inner end of a shaft 17, the outer end of which is supported by a ball bearing 11a carried by a support 11b. 30

The combined bore in the support 13 and cap 14 is internally threaded at 18 so that a nozzle 19 can be screwed in when the assemblage is made. A tightening of the nuts that hold the cap 14 down will then clamp upon the threads so 35 that there is little possibility of the nozzle 19 becoming loose. A loosening of the nuts enables unscrewing of the nozzle for any desired purpose.

The forward extremity of the nozzle 19 which, as seen in the drawing, is a tube, is turned down 40 at 20 (Fig. 3) so as to be thinned at the end, and is then split at 21 at a number of places so as to render the thinned end flexible. The purpose of the foregoing thinning is to taper the open end of the nozzle and enable the slipping of the tamp 45 bag 22 into place more quickly and easily than would otherwise be possible. One of the bags is shown in position in Fig. 1, another being held in the hand of the operator in readiness for emplacement when the first bag is filled by the operation of the machine. 50

Filling is accomplished by an auger 23, which operates in the curved terminal 7 and nozzle 19. The forward end of the auger stops immediately behind the splits 21 (Fig. 3) thereby avoiding 55

any restriction of the desired flexibility of the end 20. The shaft 24 of the auger is squared or may be otherwise non-circular at 25. This end fits into the correspondingly shaped socket 26 in the inner end of the previously mentioned shaft 17, the fit being loose because the clay packed around the auger holds it in place. The latter has a large driven pulley 27 keyed to it.

A V-belt 29 extends from the driven pulley 27 to a drive pulley 30 on the shaft 31 of a motor 32. This motor is suspended beneath the table 4 by a pair of bolts 33 (only one bolt of the pair being shown) which secure the motor only on the side farthest from the drive pulley 30. This arrangement enables the motor to take the sagged position illustrated, the weight of the motor being relied upon to maintain the tension in the belt 29 because of the weight that is imposed thereon at the pulley 30. At the same time the belt 29 acts as a friction release, enabling slipping of the belt in the event of the possibility of iron or other solid matter getting into the auger and obstructing its rotation.

The motor 32 is operated by electrical current from any convenient source. The wires 34 are connected between the motor and said source. A switch 35 is conveniently operated by the foot lever 36 and in practice this lever, which is in the nature of a treadle will be placed on the floor within reach of the operator's foot, so that he can start and stop the motor at will when bags are emplaced and removed.

The operation is thought to be obvious from the description, but a brief review may be to advantage. The hopper 5 is filled with screened clay. A bag 22, of which a supply will be kept at hand, is slipped over the nozzle 19 and held in place by one of the hands of the operator. The motor 32 is started by stepping on the treadle 36. The au-

ger 23 feeds the clay into the bag which gradually slips off of the nozzle (arrow *a* Fig. 1), as it is filled. When the bag comes off the operator has only to crimp the end and if he is quick enough he can slip the next bag on without stopping the motor. However, the treadle switch 35 is provided for the purpose of stopping and starting the motor as may be needed and when the next bag is slipped on the operation is simply a repetition of that which has already been stated.

I claim:

1. A bag filling machine comprising a hopper which has a tubular terminal and an axially aligned shaft opening, the end of the terminal being extended beyond the front limit of the hopper, a nozzle, in continuation of said extension, means constituting a partial support for the hopper and at the same time clamping the extension and nozzle together, a drive shaft entering the hopper through said opening and fitting said opening fairly closely, an auger situated in the hopper, tubular terminal and nozzle, and coupling means connecting the auger and drive shaft, being readily disconnectible upon loosening the clamping means, removing the nozzle and pulling the auger out of the tubular extension.

2. In a bag filling machine, a hopper having a tubular terminal which includes an extension, supporting means for the hopper including a support on which said extension is rested and which has a cap that bears on the extension, a nozzle which is secured into the assembled support and cap, the tightening down of the cap clamping the screw threads so that the nozzle will not come loose, and an auger operating in the tubular extension and nozzle for conveying the material from the hopper to the outlet end of the nozzle.
